STOOL

Arnold C. Martinelli, Lake Shore Drive,
Rawdon, Quebec, Canada

Filed Nov. 27, 1972, Ser. No. 309,652

Term of patent 14 years

Int. Cl. D6—01
U.S. Cl. D6—33

FIG. 1.

FIG. 2.

FIG. 3.

FIG. 4.

FIG. 5.

FIG. 6.

FIG. 1 is a front elevational view of a stool showing my new design;

FIG. 2 is a rear elevational view;

FIG. 3 is a left side elevational view;

FIG. 4 is a top plan view;

FIG. 5 is a bottom plan view; and

FIG. 6 is a transverse sectional view in elevation taken through the center of FIG. 4 looking from rear to front.

I claim:

The ornamental design for a stool, as shown.
